CLEANING CLOTH WITH COMBINED SCRAPER AND HANG-UP ELEMENT

Barclay A. Kingman, Orange, N. J., assignor to
Metal Textile Corporation, Roselle, N. J., a corporation of Delaware

Application January 6, 1950, Serial No. 137,101

1 Claim. (Cl. 15—118)

1

This invention relates to improvements in cleaning and scouring cloths for use in cleaning soiled surfaces generally, and especially for cleaning cooking and other utensils and articles of various kinds.

The invention has for an object to provide a flexible cleaning cloth, which may be of either abrasive or non-abrasive character, and to provide such cloth with a novel edged scraper element which is incorporated therewith as a unitary part thereof.

The invention has for a further object to provide, in combination with a cleaning cloth, a scraper element of such novel form and structure and so related to the body of the cloth that, in addition to its function as a scraping means, the same also provides a means for hanging up the cloth when the latter is not in use.

An illustrative embodiment of the invention is shown in the accompanying drawings, in which—

Fig. 1 is an obverse face view of a cleaning cloth according to this invention; Fig. 2 is a fragmentary reverse face view thereof; Fig. 3 is a fragmentary longitudinal sectional view, taken on line 3—3 in Fig. 1, but drawn on an enlarged scale; and Fig. 4 is a fragmentary side elevational view in part section, showing operative application of the scraper element of the cleaning cloth to a surface undergoing cleaning treatment.

Similar characters of reference are employed in the above described views, to indicate corresponding parts.

In the drawings, the reference character 10 indicates the body of a cleaning cloth which may be made of any suitable flexible sheet material, woven, knitted or felted cloth, or terry cloth or other form of pile fabric. The cleaning cloth body 10 may be treated to provide the same with a mildly abrasive surface, if so desired. For example, the cleaning cloth may comprise a body of terry cloth provided with a coating containing an abrasive filler such as disclosed in United States Patent 1,961,911.

The cloth 10 may be provided in any suitable size and of any selected peripheral shape. Preferably, the marginal portions 11 of the cloth body are suitably treated to render the same non-raveling and non-fraying.

Attached to the body 10 of the cleaning cloth, preferably at a point adjacent a margin or margins thereof, as e. g. within a corner of a square cloth or cloth of other polygonal peripheral shape, is a scraper element. This scraper ele-

ment, in a preferred form thereof, comprises a metallic eyelet or grommet-like structure, having a tubular mid-section 12 which extends through the body 10 of the cloth. Such mid-section 12 of the scraper element terminates at one end in an annular gripper flange 13 and at its opposite end in an annular anchoring member or flange 14. Said anchoring member 14 may be of scored or split formation as shown, or of coiled or rolled formation with or without a cooperative washer as sometimes provided in grommet-like structures. The body 10 of the cloth is embraced and gripped between said gripper flange 13 and said anchoring member 14, whereby to immovably engage the scraper element with and to securely fasten the same to said body 10 of the cloth as a unitary part thereof. Integral with the gripper flange 13, to project therefrom, is an outwardly and downwardly inclined annular scraper member 15, the free margin of which provides a scraping edge 16 which lies in a plane outwardly offset from the plane of the adjacent face surface of the body 10 of the cloth.

When it is desired to make use of the scraper element with which the cleaning cloth is thus provided, the cloth is grasped in the operator's hand in such manner as to oppose the scraper member 15 to a surface desired to undergo cleaning treatment, and so that the index finger of the operator's grasping hand may press down upon the scraper element (see Fig. 4). When the cleaning cloth is so held, the operator can thereupon slide the scraping edge 16 of the scraper member 15 back and forth over the surface operated upon. Such movement, as thus transmitted to the scraper element, causes the scraper member 15 to plow against encrusting substances or dirt which adheres to the surface under treatment, so that the scraping edge 16 of said scraper element 15 will quickly and easily loosen and detach the adherent encrusting substances or dirt from said surface, whereupon said substances and dirt can thereafter be easily and quickly washed or wiped away by wiping the surface with the body 10 of the cleaning cloth. It will be obvious that a very efficient and easily manipulatable cleaning instrumentality is provided, by use of which hard adherent dirt can be readily detached from soiled surfaces, so that further and final cleaning of said surfaces is greatly expedited. It will, therefore, be understood that the device of this invention provides a cleaning instrumentality of which is well adapted for operation upon all sorts of soiled

surfaces, and which is especially efficient for use as a means for cleaning pots, pans and other kitchen, household and other utensils.

Owing to the eyelet or grommet-like form of the scraper element of this invention, the same is adapted to serve another function in addition to its scraper function, viz. as a convenient means for hanging up the cleaning cloth which is equipped therewith, when said cleaning cloth is not in use.

Although a preferred form of scraper element for incorporation in a cleaning cloth has been shown in the drawings and above described, it will be obvious that the specific form of said element, and of the means for attaching the same to the body of a cleaning cloth, is subject to more or less variation within the scope of the here following claim.

Having now described my invention, I claim:

The combination with a flat flexible cleaning cloth of a rigid scraper element, said element comprising a metallic eyelet having a tubular mid-section extending through an opening in the cloth adjacent to a marginal edge thereof, said mid-section terminating at its opposite ends in outwardly extending annular flanges turned one toward the other between which the intervening

portions of said cloth surrounding said mid-section are gripped, whereby to affix said eyelet to the cloth, one of said flanges having an annular marginal portion projecting radially therefrom in angularly inclined outwardly offset relation to the plane of the adjacent face of the cloth, thus providing the cloth with a scraper element offset from said face of the cloth, and the tubular mid-section of the eyelet providing

10 a through opening by which the cloth can be hung up when not in use.
